UNITED STATES PATENT OFFICE.

JOHN W. CHESROWN, OF MANSFIELD, OHIO.

BURIAL-VAULT.

No. 918,126.

Specification of Letters Patent. Patented April 20, 1909.

Application filed November 16, 1907. Serial No. 402,537.

To all whom it may concern:

Be it known that I, JOHN W. CHESROWN, a citizen of the United States, residing at Mansfield, in the county of Richland and 5 State of Ohio, have invented a new and useful Burial-Vault, of which the following is a specification.

This invention relates to burial vaults or crypts and has for its object to provide a 10 burial vault having a central passage way and provided with a plurality of compartments or catacombs disposed on opposite sides of the passage way and each adapted to receive a coffin or casket, said compartments being arranged in vertical tiers or 15 rows and capable of being hermetically sealed so as to render the same air and moisture proof.

A further object of the invention is to provide a burial vault the several compartments 20 of which are each formed of a metal sheath or casing having its exterior walls covered with a jacket of cement, concrete or other plastic material, said compartments being 25 constructed separately and subsequently arranged in superposed order on each side of the passage-way.

A further object is to provide a removable inscription plate or slab for the closure of 30 each compartment and further to extend the lower walls of the several compartments longitudinally beyond the adjacent closures to produce a terminal supporting shelf.

A still further object of the invention is to 35 generally improve this class of devices so as to increase their utility, durability and efficiency.

Further objects and advantages will appear in the following description, it being 40 understood that various changes in form, proportions and minor details of construction may be resorted to within the scope of the appended claims.

In the accompanying drawings forming a 45 part of this specification: Figure 1 is a perspective view of a burial vault constructed in accordance with my invention. Fig. 2 is a vertical sectional view of a portion of the same. Fig. 3 is a perspective view of 50 one of the metallic sheaths detached. Fig. 4 is a top plan view partly in section showing the manner of locking the closure and inscription plate in position on the metallic sheath. Fig. 5 is a detail front elevation, 55 one of the inscription slabs being shown in position and the other removed. Fig. 6 is a

detail sectional view showing the manner of fastening the slabs.

Similar numerals of reference indicate corresponding parts in all of the figures of 60 the drawings.

The improved burial vault comprises a structure 5 formed of stone, concrete or other suitable material, said structure being provided with a centrally disposed passage way 65 or lobby 6 of sufficient size to accommodate the funeral attendants.

Disposed on opposite sides of the passage way 6 are a plurality of compartments or catacombs 7 each of which is adapted to receive a coffin or casket, said compartments being preferably arranged in vertical rows or tiers, as shown. The compartments 7 are each preferably in the form of an elongated metallic sheath or casing 8 having its rear 75 end closed and its front end open to permit the ready insertion or removal of a casket or coffin, the metal forming the body of the sheath being extended longitudinally beyond the open end thereof to produce a terminal 80 supporting shelf 9. The shelves 9 of the several tiers or rows are disposed in horizontal alinement and the metal forming each shelf is preferably bent downwardly to form an angular extension 10 to which may be secured by bolts or similar fastening devices 11 85 a strip of marble or stone 12 thereby to give an ornamental appearance to the interior of the vault.

The several sheaths 8 are covered with a 90 protective jacket 13 of cement, concrete or similar plastic material, said jackets being molded on or otherwise secured to the sheath and the latter subsequently placed in position within the vault, as best shown in Fig. 2 95 of the drawings. Extending laterally from the exterior walls of each sheath and preferably embedded in the plastic jacket 13 are a series of lugs or projections 14 each having a threaded socket 15 formed therein for the reception of a fastening device 16, which latter serves to lock the removable cover or closure 17 against accidental displacement. The cover or closure 17 is preferably stamped or otherwise formed of metal and is bent laterally within the adjacent compartment to form a marginal stop shoulder 18 adapted to bear against the interior walls of said compartment, there being a packing of asbestos or similar material 19 secured to the inner 105 face of the cover or closure 17 and interposed between the marginal flange 20 of the door 110

- and the adjacent end of the metallic sheath thereby to hermetically seal the compartment and thus render the latter air and moisture proof. A transverse strip 21 is secured 5 to or formed integral with the bottom of each sheath for engagement with the interior face of the adjacent door or closure 17 thereby to assist in limiting the inward movement of said door.
- 10 Disposed in front of each door or closure 17 is a plate or slab 22, which latter is preferably formed of marble or stone and adapted to receive a suitable inscription, as best shown in Fig. 5 of the drawings. The slab 22 is provided 15 with metal bushings 23 adapted to receive the fastening devices 16 so that when the screws are adjusted to secure the slab in position, said bushings will prevent cracking or otherwise injuring the slab.
- 20 Extending vertically from the supporting shelves 9 of the several sheaths are stop pins or lugs 24 which co-act with suitable wedges 25 and thus prevent accidental displacement of the lower edges of the slabs or plates.
- 25 Attention is here called to the fact that the screws or fastening devices 16 serve the double function of retaining the closures 17 and slabs 22 in position on the sheaths.
- The walls of the several sheaths or compartments are each pierced by a branch pipe 26 which communicates with a drain pipe 27 extending vertically of the vault and having its lower end embedded in the ground, as shown, the lower walls of the sheath being 35 preferably disposed at a slight angle or inclination to permit drainage of the same.
- In constructing the vault the several compartments are preferably formed separately and disposed one above the other within the 40 vault on each side of the passage way, as best shown in Fig. 1 of the drawings, a quantity of mortar, cement or other binding material being interposed between the protective jackets of the several sheaths in order to form 45 a strong, rigid structure.
- It will here be noted that the supporting shelves 9 not only serve to sustain the weight of the coffin or casket when positioning the same within or removing the casket from the 50 compartment but also form ledges upon which may be supported a vase containing flowers and the like.
- Having thus described the invention what is claimed is:
- 55 1. A burial vault having a compartment formed of a metallic sheath open at one end and provided with a plurality of laterally extending lugs, the lower wall of the sheath being extended longitudinally to form a supporting shelf, a closure for the open end of the sheath, fastening devices piercing the closure and lugs, an inscription slab forming a housing for the closure, and a plastic jacket surrounding the sheath.
- 60 65 2. A burial vault having a compartment formed of a metallic sheath open at one end and provided with a plastic jacket, lugs extending laterally from the open end of the sheath and embedded in the jacket, the lower wall of the sheath being extended longitudinally to form a supporting shelf, pins extending vertically from the supporting shelf, a closure for the open end of the sheath, fastening devices piercing the closure and lugs, respectively, a slab forming a housing for the closure, and wedges interposed between the pins and slab.
3. A burial vault having a compartment formed of a metallic sheath open at one end and having its lower wall extended longitudinally to form a supporting shelf, a strip extending transversely across the sheath and secured to the bottom thereof, a plastic jacket surrounding the sheath, lugs extending laterally from the exterior walls of the sheath at the open end thereof, a closure bearing against said lugs, a packing interposed between the closure and the open end of the sheath, fastening devices piercing the closure and lugs, respectively, pins extending vertically from the shelf, a slab forming a housing for the closure, and wedges interposed between the pins and slab.
4. A burial vault including a structure having a passageway and provided with a plurality of compartments arranged in tiers on opposite sides of said passageway and each formed of an elongated metal sheath open at one end and provided with a plastic jacket, the lower wall of each sheath being extended longitudinally to form a supporting shelf, the terminal of which is bent downwardly to produce a depending flange, closures for the open ends of the sheaths and having their intermediate portions bent inwardly to form a marginal shoulder adapted to bear against the interior walls of the adjacent sheath, lugs secured to the exterior walls of the sheaths, fastening devices piercing the closures and engaging the lugs, pins extending vertically from the shelves, slabs forming housings for the closures, and wedges interposed between the pins and slabs, respectively.
5. A burial vault including a structure having a passage way and provided with a plurality of compartments arranged in tiers on opposite sides of the passage way and each formed of an elongated metallic sheath having one end thereof open and provided with a plastic jacket, said compartments being disposed in superposed order with the plastic jackets of adjacent sheaths united with a binding material, lugs extending laterally from the exterior walls of each sheath and having threaded openings formed therein, closures engaging the open ends of the sheaths, a packing interposed between each closure and the open end of the adjacent sheath, the lower walls of said sheaths being extended longitudinally to form supporting shelves.

terminating in depending flanges adapted to register with the flanges of adjacent sheaths, pins extending vertically from said shelves, inscription slabs forming housings for the 5 closures, and wedges interposed between the pins and slabs for locking the latter against accidental displacement.

In testimony that I claim the foregoing as my own, I have hereto affixed my signature in the presence of two witnesses.

JOHN W. CHESROWN.
